UNITED STATES PATENT OFFICE.

ERIC ENGBLOM, OF DENVER, COLORADO.

HITCHING-POST.

1,064,200.

Specification of Letters Patent. Patented June 10, 1913.

Application filed April 12, 1912. Serial No. 690,398.

To all whom it may concern:

Be it known that I, ERIC ENGBLOM, citizen of the United States, residing in the city and county of Denver and State of Colorado, have invented certain new and useful Improvements in Hitching-Posts; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to improvements in hitching posts, my object being to provide a device of this character which shall be simple in construction, reliable, durable and efficient in use.

20 More specifically, my improvement consists of a post whose body portion is preferably composed of cement or other similar material adapted when in plastic form to be molded into any desired shape. Within

25 the central portion of the body of the post is located a metallic tube in which is placed a weight connected with one extremity of a chain whose opposite extremity is exposed outside the post and preferably contains a

30 snap-hook adapted to be connected with a ring of a horse's bridle, or other similar attachment to the horse or other animal which it is desired to hitch. Communicating with the tube located within the body 35 of the post is a passage leading to the outside through which the chain passes. This outer passage is equipped with a plate in which is formed a slot of irregular shape communicating with the main opening.

40 The chain is of such size that it slides freely through the main opening, and when a sufficient length of the chain is outside the post, the chain, where it passes through the opening in the outer plate, is slipped into the

45 slot communicating with the said opening thus locking the chain against further movement and supporting the weight in the desired position of adjustment. As soon as the animal is unhitched, the chain may be

50 moved from the locking slot into the main opening when the downward movement of the weight will draw the chain into the post, leaving only its snap-hook extremity exposed.

55 Having briefly outlined my improved construction, I will now proceed to describe

the same in detail, reference being made to the accompanying drawing.

In this drawing, Figure 1 is an elevation of my improved hitching post. Fig. 2 is a 60 central longitudinal section of the same. Fig. 3 is a view of the plate containing the opening through which the chain passes as it leaves the post. This view is taken looking in the direction of arrow 3 Fig. 2, but 65 shown on a larger scale. Fig. 4 is a sectional view of the portion of the tube which communicates with the outer passage through which the chain passes. The parts in this view are shown on a larger scale than 70 in Figs. 1 and 2.

The same reference characters indicate the same parts in all the views.

Let the numeral 5 designate the body of the post which is preferably composed of 75 cement. This post, so far as its exterior shape is concerned, may be of any suitable design. It is also evident that its size may be regulated as desired. Cast or molded within the body of the post is a tube or 80 pipe 6 whose upper extremity is connected with a coupling-member 7 by means of screw-threads. This coupling is also connected at its upper extremity with a short-pipe-member 8. The coupling has an open- 85 ing in one side as shown at 9, the said opening being surrounded by a nipple 10 into which is threaded a short pipe-member 12 whose outer extremity is threaded to receive a cap-plate 13 having a main opening 90 14 communicating with the central tube. Communicating with the main opening is a curved slot 15 leading to a horizontally-arranged slot 16. Within the tube is located a weight 17 connected with one extremity of a hitching chain 18 the opposite extremity of the chain being provided with a snap-hook 19 which is located outside the post whereby it is always exposed for hitching purposes. The upper portion of the 100 chain engages an anti-frictional roller 20 which is located at the angle formed by the tubular member 12 and the body of the tube within the post. The chain, as it passes over the roller, changes its direction and passes 105 out through the tubular member 12 and through the opening 14 until the desired length of chain is exposed. Then the chain is passed from the main opening of the plate 13 through the grooved slot 15 into the slot-member 16, which is of sufficient width to receive a chain with the link flat-wise, but 110

which will not allow the adjacent link to pass through, since, in the style of chain shown, the adjacent links occupy positions at right angles to each other. For this reason, when the chain is moved into the slot 16, it will remain in the adjusted position. By virtue of this construction, only the exact length of chain desired need be exposed beyond the post, consequently the animal may be so hitched that he cannot get his head to the ground.

From the foregoing description the use of my improved hitching post will be readily understood.

Assuming that the chain is in the position illustrated in Fig. 1 of the drawing, if it is desired to hitch the animal, the exposed snap-hook extremity of the chain will be grasped by the user and passed from the slot-member 16 through the slot-member 15 into the opening 14. The chain may then be pulled out of the post to the desired length, the snap-hook being connected with the ring of the animal's bridle, or with any other suitable device for hitching purposes. A link of the chain is then slipped from the opening 14 through the slot 15 into the slot-member 16, where it will be locked against movement in either direction except by design.

The shape of the openings 14, 15, and 16 of the cap plate constitutes an important part of my invention. The curved slot 15 is of such a width as to permit a link of the chain to pass from the opening 14 to the slot 16, or vice versa, only when guided by the hand. With my improved construction there is no liability that the chain will be unfastened through shaking of the head of the animal hitched.

Where the body of the post is composed

of cement or similar material, the tube is composed of metal and forms a metal reinforcement for the cement or other suitable material. In this event, the tube performs a double function constituting a receptacle for the weight and a run-way for the chain connected therewith, and at the same time provides the necessary metal reinforcement for the cement body-member.

45

50

Having thus described my invention, what I claim is:

A hitching post having a body member equipped with a longitudinally disposed passage and a laterally communicating passage near the upper end of the post, a cap plate applied to the post at the outer extremity of the lateral passage, said plate having an opening composed of a circular portion, a straight horizontal slot and a curved slot joining said circular portion and straight slot and extending from said straight slot at approximately a right angle; a weight slideable in the longitudinal passage, a chain attached to said weight and extending through said passages and the opening in said plate, the links of said chain being of a size to permit the chain to slide freely through the circular portion of the opening in the cap plate and to permit any one link to be guided through said curved slot into said straight slot, but at the same time preventing any accidental passage from the circular portion to the straight slot, or vice versa.

75

In testimony whereof I affix my signature in presence of two witnesses.

ERIC ENGBLOM.
